US0D1086572S

(12) **United States Design Patent** (10) Patent No.: **US D1,086,572 S**
(45) Date of Patent: ** Jul. 29, 2025

(54) **CONTAINER FOR COSMETIC STICK**

(71) Applicant: **Kolmar Korea Co., Ltd.**, Sejong-si (KR)

(72) Inventors: **Jung Mo Jung**, Seoul (KR); **Jin Sung Lee**, Seoul (KR); **Sang Geun Han**, Seoul (KR); **Hyung Sang Kim**, Seoul (KR)

(**) Term: **15 Years**

(21) Appl. No.: **35/522,481**

(22) Filed: **Sep. 27, 2023**

(80) **Hague Agreement Data**

Int. Filing Date: **Sep. 27, 2023**

Int. Reg. No.: **DM/234969**

Int. Reg. Date: **Sep. 27, 2023**

Int. Reg. Pub. Date: **Sep. 27, 2024**

(30) **Foreign Application Priority Data**

Mar. 31, 2023 (KR) 30-2023-0012407

(51) **LOC (15) Cl.** **28-02**

(52) **U.S. Cl.**

USPC **D28/76**
